US00D930586S

(12) **United States Design Patent** (10) **Patent No.:** **US D930,586 S**
(45) **Date of Patent:** ** *Sep. 14, 2021

(54) **MOTOR ASSEMBLY OF AN ELECTRIC SCOOTER**

(71) Applicant: **FUKUTA ELECTRIC & MACHINERY CO., LTD.**, Taichung (TW)

(72) Inventor: **Chin Feng Chang**, Taichung (TW)

(73) Assignee: **FUKUTA ELECTRIC & MACHINERY CO., LTD.**, Taichung (TW)

(*) Notice: This patent is subject to a terminal disclaimer.

(**) Term: **15 Years**

(21) Appl. No.: **29/767,759**

(22) Filed: **Jan. 25, 2021**

Related U.S. Application Data

(63) Continuation-in-part of application No. 29/672,616, filed on Dec. 6, 2018, now abandoned.

(57) **CLAIM**

The ornamental design for a motor assembly of an electric scooter, as shown.

DESCRIPTION

FIG. 1 is a front-right-top perspective view of a motor assembly of an electric scooter in accordance with the present invention;

FIG. 2 is a front-left-bottom perspective view thereof;

FIG. 3 is a rear-right-bottom perspective view thereof;

FIG. 4 is a rear-left-top perspective view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

The broken lines in the drawings are for the purpose of illustrating portions of the motor assembly of an electric scooter that form no part of the claimed design.

1 Claim, 10 Drawing Sheets
